UNITED STATES PATENT OFFICE.

FREDRIK LJUNGSTRÖM, OF BREVIK, LIDINGON, SWEDEN, ASSIGNOR TO AKTIEBOLAGET LJUNGSTRÖMS ANGTURBIN, OF STOCKHOLM, SWEDEN, A CORPORATION.

TURBINE-DRIVEN LOCOMOTIVE.

Application filed October 19, 1921. Serial No. 508,895.

To all whom it may concern:

Be it known that I, FREDRIK LJUNGSTRÖM, chief engineer, a subject of the King of Sweden, residing at Brevik, Lidington, 5 Sweden, have invented certain new and useful Improvements in Turbine-Driven Locomotives, of which the following is a specification.

In turbine driven locomotives it has 10 always been connected with difficulties to arrange the steam conduits in a satisfactory manner, said difficulties being particularly prominent in case of each of the steam boiler and the condenser being placed on a separate 15 carriage, since in such case the steam conduit or conduits disposed between the carriages are compelled to effect a springy or articulate movement. The turbine has preferably been placed on the condenser carriage, and by this the advantage has been 20 obtained that the said movement of the steam conduit between the two carriages can be effected in the high pressure steam conduit between the steam boiler and the 25 turbine which conduit has a considerably smaller diameter than the waste steam outlet conduit. In case the transmission of power is effected electrically, it has been 30 possible to connect the latter conduit directly to the condenser, and at the same time the driving shaft of the steam turbine has been capable of being connected immediately to the electric generator. Besides, in locomotives in which the transmission of power 35 from the turbine to the driving wheels is effected directly by means of toothed gearing and connecting rods it has proved difficult to eliminate the stresses occurring in the gearing and the turbine owing to the reciprocating crank movement, in case the turbine be rigidly connected with the condenser. Said stresses effected by the crank motion cause tensions and unequal engagement of tooth and gearing and may be 40 removed in known manner by mounting the gearing and the casing enclosing the same movably, for instance on the frame, the obliquely acting forces being however transmitted to the turbine and its toothed wheels, 45 unless the turbine, for instance by the arrangement of a joint in the outlet conduit to the condenser, be permitted to follow all the movements of the gear.

This invention relates to a device the object of which is to prevent such obliquely

acting forces in the turbine and consists in this viz., that the turbine is rigidly connected with the condenser but in flexible connection with the driving wheels.

A preferred embodiment of the invention 60 is illustrated in the accompanying drawings in which—

Fig. 1 is an end view of a condenser carriage, a portion of the frame being broken away. Fig. 2 is a side view of the condenser carriage and Fig. 3 shows a detail on an enlarged scale.

Referring to the drawings, the main turbine 1 is rigidly connected with the condenser which in this case consists of a water tank 2 and an air-cooled part 2^a supported directly by a frame 3. The turbine 1 is by means of a toothed gearing connected with the cranks and the connecting rods actuating the driving wheels. The casing 4 enclosing and supporting the toothed gearing is mounted on the frame 5 forming a part of the frame 3 in such manner that the casing 4 is movable to a certain extent, which result is effected in known manner by double journalling of the crank shaft 8 of the gearing.

The shaft of the turbine 1 is by means of a diaphragm coupling 6 connected with the first pinion 7 of the gearing, and owing to 85 this coupling the casing 4 together with all the toothed wheels may be adjusted independently of the turbine so as to effect equal pressure on the teeth without obliquely acting stresses being transmitted to the turbine.

Fig. 3 illustrates the flexible connection of the turbine with the gearing by means of a diaphragm coupling. In this figure, 10 indicates the turbine shaft, 6 a diaphragm coupling connecting the turbine shaft 10 with the one end of a shaft 12 passing freely through the pinion 7. The other end of the shaft 12 is by means of a diaphragm coupling 13 connected with a hollow shaft 14 to which the toothed wheel 7 is rigidly attached. In this manner the wheel 7 may follow the different movements of the other gear wheels without interfering with the turbine which may be rigidly attached.

Other arrangements to effect the movable connection of the turbine with the toothed gearing or the driving wheels than that shown in the drawing are possible. Thus for instance joints or the like may be dis-

posed in the turbine shaft. Such arrangements are however comprised in the principle of the invention.

What I claim as new and desire to secure by Letters Patent of the United States is:—

1. In turbine driven locomotives in which movement is transmitted from the turbine to the driving wheels by means of crank, connecting rod and intermediate driving device and in which a condenser is placed on a carriage, separate from the boiler carriage, the arrangement that the turbine is rigidly connected to the condenser but flexibly connected with the driving device.

15 2. An arrangement according to claim 1

characterized in that part of the condenser to which the turbine is rigidly connected, consists of a water tank.

3. An arrangement according to claim 1, in which the turbine is mounted above a toothed gearing connecting it with the driving wheels, characterized by the turbine being connected with the toothed gearing by means of a diaphragm coupling.

In testimony whereof I affix my signature 25 in presence of two witnesses.

FREDRIK LJUNGSTRÖM.
